UNITED STATES PATENT OFFICE.

CHARLES FORD, OF LOWELL, MASSACHUSETTS.

PILE-WIRE.

SPECIFICATION forming part of Letters Patent No. 479,211, dated July 19, 1892.

Application filed June 4, 1891. Serial No. 395,055. (No model.)

To all whom it may concern:

Be it known that I, CHARLES FORD, a citizen of the United States, residing at Lowell, in the county of Middlesex and Commonwealth 5 of Massachusetts, have invented a certain new and useful Improvement in Pile - Wires, of which the following is a specification.

My invention relates to pile-wires; and it consists in the improved means hereinafter 10 described of securing such wires to their heads.

In the accompanying drawings, Figure 1 is a side elevation of a pile-wire and head made according to my invention, the free end of 15 the wire being provided with a cutting-edge; Fig. 2, a side elevation of a pile-wire without a knife and a head of slightly-different form from that shown in Fig. 1; Fig. 3, a horizontal cross-section on the line 3 3 in Fig. 1; 20 Fig. 4, a similar section on the line 4 4 in Fig. 2; Fig. 5, a vertical section on the line 5 5 in Fig. 1; Fig. 6, a vertical section on the line 6 6 in Fig. 2.

Pile-wires such as are used in forming the 25 loops which project from the face of pile fabrics require to be narrow enough to make the loops of the proper size and stiff enough to reach entirely across the fabric without sagging or lateral bending or displacement. 30 They are therefore usually made of steel, tempered, and are secured in heads adapted to be engaged by suitable devices for withdrawing the wires from the loops after the loops are formed, and the heads require to be very 35 thin in order to allow several pile-wires to remain in their respective rows of loops for some time after the last row of loops is formed, five or six or more wires being in an equal 40 number of rows of loops at the same time in order to support the loops nearest the "making end" of the fabric, the pile-wire farthest from the making end being first drawn from the loops, so that the distance from the middle of one head to the middle of the next adjacent 45 head cannot be greater than the distance from the middle line of one row of loops to the middle line of the next adjacent row of loops. The heads are therefore about a sixteenth of an inch in thickness and are usually 50 made of sheet metal slotted entirely through to receive the end of the wire proper,

which is secured in the slot so formed by brazing. Brazing the wires into the heads usually draws the temper of the wire for a short distance from the heads and makes the 55 wires extremely liable to be bent laterally at this point, it requiring considerable force to withdraw the wires from the loops, especially such of the wires as have been left in the loops over night or over a Sunday or other holiday, 60 the loops frequently contracting on the wires and holding them so firmly that where the pile is to be cut it is frequently cut by hand before attempting to remove the wires. Again, the strain of the wires on the heads, where 65 the heads are slotted entirely through, frequently spreads the sides of the slot apart and releases the wires; and the wires are more easily twisted out of the slots because said wires are united to the heads only at the top 70 and bottom of the wires.

By the means hereinafter described I prevent the spreading apart of the sides of the wire-receiving slot and provide a greater contact-surface between the head and the wire. 75

In the drawings two kinds of wires A A' are shown, the wire A (represented in Figs. 1, 3, and 5) being a wire nearly rectangular in cross-section, but slightly rounded at the corners at a, (see Fig. 5,) and at the outer 80 free end or end farthest from the head B flattened and vertically or upwardly enlarged and sharpened to form a cutting-edge a², which cuts the loops as the pile-wire is withdrawn from them to make a fabric similar to velvet 85 or cut velvet, plush, velveteens, or Wilton carpets. The wire A' (shown in Fig. 2) is more nearly round, but has slightly-flattened vertical sides, and is straight and of uniform cross-section, and does not cut the loops when 90 withdrawn from them, but leaves them whole, as in uncut or terry velvet and Brussels carpets. In both cases the wires proper A A' are usually secured in their respective heads B B' by the means above described. 95

Instead of slotting the heads entirely through in the usual manner, I drill a hole b b' in the head B B' of a sufficient diameter to receive the ends of the wire and groove or slot the head at b² b³ partly through, as 100 shown at Figs. 5 and 6, from said hole b b' to the end of the head, to receive the wire and

2 closely fit the same, and after drawing the temper of the extreme head end of the wire—say for about a quarter of an inch from the end—I insert the wire A A' endwise in the 5 slot so formed, and by means of a punch force the end of the wire into the hole b b' and then "sweat" or solder with soft solder the head and the wire proper together, this operation not drawing the temper of the wire 10 as brazing would do, and the preliminary drawing of the wire above mentioned not extending the entire length of the slot in the head, so that when the operation is completed the part of the wire outside of the 15 head and for some distance within the slot still retains its hardness and temper. The slot b² b³ is preferably narrower at its open side, as shown in Figs. 5 and 6, so as to be in effect a dovetail slot, to prevent the wire being drawn laterally out of its slot, while the 20 engagement of the wire with the hole b b' prevents the wire being drawn endwise out of said slot and also, assisted by the shape of said wire and said slot, prevents the wire from 25 turning in said head.

I claim as my invention—

1. The combination of a flat metallic pile-wire head provided in one of its sides with a groove or slot cut to a depth less than the 30 thickness of said head and a pile-wire secured in said slot, substantially as described.
2. The combination of the flat metallic head provided with a groove or slot of less depth than the thickness of said head, said 35 slot being narrowest at its open side, and the pile-wire inserted in said slot and secured therein, as and for the purpose specified.
3. The combination of the flat metallic head provided with a hole and provided in

one of its sides with a groove or slot extending nearly to the opposite side of said head and from said hole to the end of said head and the pile-wire inserted in said slot and bent into said hole, as and for the purpose specified.

4. The combination of the head provided with a hole and with a slot or groove of less depth than the thickness of said head and extending from said hole to the end of said head, said slot being narrower at its open side, and the pile-wire inserted in said slot and bent into said hole, as and for the purpose specified.

5. The combination of the flat metallic head provided with a hole and with a slot or groove extending nearly to the opposite side of said head and from said hole to the end of said head and the pile-wire inserted in said slot and bent into said hole and secured to said head by sweating or soldering with soft solder, as and for the purpose specified.

6. The combination of the head provided with a hole and with a slot or groove of less depth than the thickness of said head and extending from said hole to the end of said head, said slot being narrower at its open side, and the pile-wire inserted in said slot and bent into said hole and secured to said head by sweating or soldering with soft solder, as and for the purpose specified.

In witness whereof I have signed this specification, in the presence of two attesting witnesses, this 1st day of June, A. D. 1891.

CHARLES FORD.
